DESIGN FOR A PENCIL HOLDING ATTACHMENT FOR TRISQUARES

John A. Phillips, Oakland, Calif.

Application April 27, 1943, Serial No. 110,055

Term of patent 14 years

To all whom it may concern:

Be it known that I, John A. Phillips, a citizen of the United States, residing at Oakland, in the county of Alameda and State of California, have invented a new, original, and ornamental Design for a Pencil Holding Attachment for Trisquares, of which the following is a specification, reference being had to the accompanying drawing, forming part thereof.

Figure 1 is a side elevational view of a pencil

holding attachment for trisquares showing my new design.

Figure 2 is a rear elevational view thereof.

Figure 3 is a top plan view thereof.

Figure 4 is a bottom plan view thereof.

I claim:

The ornamental design for a pencil holding attachment for trisquares, as shown.

JOHN A. PHILLIPS.
